COMBUSTION METHOD AND APPARATUS

Rallston M. Sherman, Glastonbury, Conn., assignor to The Silent Glow Oil Burner Corporation, Hartford, Conn., a corporation of Connecticut

Application September 10, 1949, Serial No. 115,090

11 Claims. (Cl. 158—4)

1

My invention relates to methods of and apparatus for burning oil.

The invention has among its objects the burning of the oil in such way as to secure its complete combustion. Among other objects is to secure complete combustion of the oil while securing a high temperature of the gaseous combustion products and an incandescent surface constituting a source of radiant heat of high intensity.

The invention, however, will be best understood from the following description when read in the light of the accompanying drawing of a specific embodiment of apparatus according to the invention for practising the method according to the invention.

According to the invention, the oil in an atomized state commingled with air, to form a mixture such as that produced by the ordinary domestic gun burner, is entered into a combustion chamber and burned therein, the chamber having walls comprising heat refractory sheet metal, this sheet metal, the opposite sides of which are exposed to the interior and exterior of the chamber, presenting an extensive area provided with closely spaced perforations distributed thereover for escape of products of combustion from the chamber. This perforated sheet metal, which preferably is formed of steel having a high chromium content, may, in respect to thickness and the diameter and spacing of the perforations, be, for example but without limitation thereto, identical with that of which the combustion tubes of range oil burners commonly are formed. In this combustion chamber the oil, according to the invention, is burned with a flame of such pattern that it does not contact the combustion chamber walls, the oil being burned at such rate that the perforated area of the sheet metal throughout its extent is heated to incandescence, say from 900° to 1500° F. The chamber is substantially closed so that substantially the only air which enters it is that which is contained in the atomized oil-air mixture, and preferably is so constructed that the only escape of the products of combustion is substantially through the small perforations mentioned.

It has been found that in burning the oil in the way above described complete combustion may be secured, the combustion products after the apparatus assumes stable operation being constituted wholly by carbon dioxide, nitrogen, excess oxygen, and water vapor. The apparatus according to the invention, it has been found, assumes stable operation in from about 200 to

2

250 seconds after combustion is initiated. During this short period small amounts of carbon monoxide are produced, but not in dangerous amounts, to wit, only from about 5 to 10 parts per million parts combustion products. A typical analysis of the dry combustion product of apparatus according to the invention burning No. 2 fuel oil according to the improved method is as follows:

		Percent
10	Carbon dioxide	4.41
	Illuminants	None
	Oxygen	12.09
	Hydrogen	None
15	Carbon monoxide	None
	Ethane	None
	Methane	None
	Nitrogen	83.50
20		100.00

As a result of the absence of carbon monoxide in the combustion products, when burning oil according to the invention, the improved apparatus may be placed in a closed room or other space for heating it without danger to occupants of such room or space. This adapts the apparatus for use, for example, as a space heater in barns, potato storage houses, and the like, the same being heated by the products of combustion issuing through the above mentioned perforations of the combustion chamber and by the radiant heat emitted from the incandescent surface portions of the walls of that chamber. Furthermore, because of the total combustion of the oil, the products of combustion are entirely odorless, making it possible to heat such a space without contamination of the crop or other material stored in such space.

It has been found that the diameter of any perforations, including those above mentioned, in the combustion chamber wall permitting escape of combustion products should not exceed approximately 0.15 inch in diameter, or otherwise have a cross-sectional area greater than approximately that presented by a perforation of such diameter, namely, a cross-sectional area of approximately 0.018 square inch, as otherwise incompletely burned combustion products will escape through them usually in the form of a smoke having a pronounced odor and containing dangerous amounts of carbon monoxide. The perforations may have diameters as small as possible, and preferably are as small as can be economically produced. For practical and economic reasons these perforations are formed by use of

a punching operation employing a multiple die which forms a large number of perforations at each punching stroke, and under any ordinary condition it is not practical to so punch them with diameters much less than about 0.08 inch. Otherwise, and with smaller perforations, the perforations would have to be formed by expensive and time consuming drilling operations. Excellent results are obtained with twenty uniformly distributed perforations per square inch each of 0.078 inch diameter. It has been found, however, that the number of perforations and their sizes, whether produced by punching or drilling, may be varied so long as the total area presented by the perforations per square inch is from approximately 0.05 to 0.14 square inch.

Preferably the sheet metal constituting the perforated portion of the combustion chamber is as thin as structural requirements will permit, sheet metal about $\frac{1}{32}$ inch thick giving satisfactory results in most situations. However, this thickness is not critical, and may be varied within wide limits.

It also has been found that to secure complete combustion the cubical contents of the combustion chamber or drum should be from approximately 2300 to 4000 cubic inches per gallon of oil burned per hour, with the total perforated surface of the drum, i. e., the area of the perforations and the intervening metal, expressed in square inches from 15 to 35% of the arithmetical value of the cubical contents of the combustion chamber or drum expressed in cubic inches.

The kind of oil burned in the improved apparatus in practising the improved method is not critical, satisfactory results having been secured with ordinary commercial gasoline, kerosene, and all grades of fuel oil up to so-called No. 3 fuel oil.

Preferably the combustion chamber for structural reasons is in the form of a cylindrical drum having closed ends, through one of which ends the atomized oil-air mixture is entered, this end preferably being otherwise imperforate. Also the perforated portion of the combustion chamber or drum is preferably constituted by the cylindrical or other lateral walls of the drum. The end of the drum opposite that end through which the oil-air mixture enters may, if desired, be perforated so as to constitute part of the perforated portion of the drum. However, perforating this end of the drum seems to secure no useful effect in any ordinary case except in reducing the starting period for the apparatus to assume stable operation.

When a cylindrical drum is employed the relation between the diameter of the drum and its length is by no means critical, satisfactory results having been secured where the length of the drum is from 100 to 400% of its diameter. Examples of having their lengths within such range are drums 15 inches in diameter and 18 inches long, 22 inches in diameter and 24 inches long, 22 inches in diameter and 36 inches long, and 26 inches in diameter and 30 inches long. Other proportions between the length and diameter of the drum however may be employed, and satisfactory results have been secured with drums the length of which is less than their diameter, for example, with drums 22 inches in diameter and 18 inches long, in which particular instance the length of the drum is but about 80% of its diameter.

The amount of air admixed with the atomized oil may be that commonly employed in connection with domestic oil burners, preferably an

amount of air which will give a bright orange flame. However, as is the case with the ordinary domestic oil burner, lesser amounts of air may be employed down to that which will give a blue flame. It is advisable, as in the ordinary case of combustion apparatus, to keep the excess amount of air supplied at a minimum consistent with securing satisfactory operation, as otherwise the temperature of the combustion products will be decreased. In accordance with common practice this amount of air should be such as to give a rather small amount of excess oxygen in respect to the amount thereof which will stoichiometrically secure complete combustion, namely, from 8 to 15% excess oxygen, but preferably from about 10 to 12%.

In practising the improved method with combustion chambers designed as above described the pressure within the chamber is only very slightly above that of the surrounding atmosphere, under ordinary circumstances this pressure being only from about 0.0008 to 0.006 inch of water above that of the surrounding atmosphere.

Examples of apparatus according to the invention for practising the improved method are shown by the accompanying drawings in which

Fig. 1 is an elevation, with parts broken away, of such apparatus; and

Fig. 2 is an end view showing a modified form of the combustion chamber, corresponding to Fig. 1 as viewed from the right with parts omitted.

Referring to Fig. 1 of the drawings, the combustion chamber is in the form of a drum having the cylindrical wall 1 provided with perforations 3 distributed over its entire surface. As shown, the end 5 of the drum is closed, while the end 7 is provided with an opening 9 which receives the discharge end of a conduit 11 through the open end 13 of which the atomized oil-air mixture is discharged into the drum. As illustrated, the conduit 11 forms part of a conventional gun type burner, this burner comprising a casing 15 containing an electric motor driven fan 17 for forcing air through the conduit 11 into the drum, the amount of air being regulated in the usual manner by adjustable shutters (not shown) on the end of the casing, which shutters control the size of the air intake to the fan. As in the conventional gun type burner, a pump 19 driven by the same motor as the fan draws oil from the tank 21 and discharges it under pressure into a pipe 23 in communication with a pipe 25 positioned axially of the conduit 11, the pipe 25 having at its end adjacent the combustion chamber or drum a spray nozzle 27 for atomizing the oil. This nozzle is so designed as to secure the desired pattern of the flame and the desired amount of oil supplied the combustion chamber. Preferably positioned in the conduit 11 is a circumferential series of vanes 29 for causing a whirling action of the air discharged from the conduit so as thoroughly to mix the air with the atomized oil. The burner, as shown, is provided with an ignition spark electrode 31, and preferably is provided with the usual controls for governing the operation of the apparatus in accordance with the temperature conditions of the space heated.

If desired, the opening 9 in the end 7 of the drum may be slightly larger than the exterior diameter of the conduit 11 so as to permit expansion of the parts. Some air may flow into the drum through the clearance afforded by this opening because of the suction effect of the mixture entering the drum from the conduit 11.

and such air will mix with the mixture so that in substance all the air which enters the drum is contained in the oil-air mixture supplied it.

Although only the cylindrical portion of the drum is perforated in the form of apparatus shown by Fig. 1, the end 5 thereof also may be perforated, as above explained and as shown at 3^a in Fig. 2. As an example of the invention in which both the cylindrical walls 1 and end wall 5 of the drum are perforated satisfactory results have been secured when the outside diameter of the drum is approximately 22 inches and its outside length approximately 18 inches, the thickness of the walls 1, 5 and 7 being about 0.028 inch with the perforations 0.078 inch in diameter uniformly spaced to present twenty perforations per square inch, the apparatus under conditions of satisfactory minimum oil consumption burning 1.65 measured gallons of No. 2 fuel oil per hour, the amount of air supplied being sufficient to produce a bright orange flame, this amount of oil heating the walls of the combustion chamber to between 1300° and 1400° F.

It will be understood that within the scope of the appended claims wide deviations may be made from the forms of the invention described without departing from the spirit thereof.

What is claimed is:

1. The method of burning fuel oil to secure substantially its complete combustion without formation of carbon monoxide, utilizing a combustion chamber consisting of a drum of thin heat refractory metal exteriorly defined by lateral and end walls, which lateral walls are formed with perforations not exceeding approximately 0.018 square inch in transverse cross-section and distributed over said lateral walls in spaced relation in such number as to present approximately from 0.05 to 0.14 square inch of total transverse cross-section per square inch of perforated surface, with the total area of such surface in square inches being arithmetically approximately from 15 to 35 per cent of the arithmetical value of the cubic contents of the drum expressed in cubic inches, which method comprises burning the fuel oil in said drum by discharging it into the drum at one end thereof toward its opposite end in atomized state mixed with sufficient air to support its complete combustion, at the rate of one gallon of such oil per hour for each 2300 to 4000 cubic inches of the cubic contents of the drum, and in the form of a spray of such pattern as will produce a flame that is in such proximity to at least the lateral walls of the drum as to heat them to incandescence but is in out-of-contacting relation with all said walls of the drum so as to be surrounded by combustion products, such air being substantially the only air admitted to said drum; and discharging the combustion products from said drum substantially solely through said 60 perforations.

2. The method according to claim 1 in which the drum utilized also has like perforations in its end wall opposite its end wall through which the mixture of atomized fuel oil and air is entered, which perforations also present approximately from 0.05 to 0.14 square inch of total transverse cross-section per square inch of perforated surface, the total area of perforated surface presented by said perforated end wall and lateral walls 70 in square inches being arithmetically approximately from 15 to 35 per cent of the arithmetical value of the cubic contents of the drum expressed in cubic inches, the spray being of such pattern that the flame produced also is in such proximity 75

to said perforated end wall as to heat it also to incandescence and the combustion products being discharged substantially solely through the perforations of said lateral walls and perforated end wall.

3. Oil burning apparatus comprising a combustion chamber in the form of a drum of thin heat refractory sheet metal capable of being heated to incandescence, such drum being exteriorly defined by lateral and end walls, the lateral walls being formed with perforations constituting substantially the sole means of escape of combustion products from said drum, said perforations not exceeding approximately 0.018 square inch in transverse cross-section and distributed over said lateral walls in spaced relation in such number as to present approximately from 0.05 to 0.14 square inch of total transverse cross-section per square inch of perforated surface, 20 with the total area of such surface in square inches being arithmetically approximately from 15 to 35 per cent of the arithmetical value of the cubic contents of the drum expressed in cubic inches, one end wall of the drum having an opening; burner means for discharging into said drum through said opening atomized fuel oil mixed with sufficient air to support its combustion at the rate of one gallon of such oil per hour for each 2300 to 4000 cubic inches of the cubic contents of said drum; said burner means comprising an oil atomizing spray nozzle associated with said opening, from which nozzle the oil is so discharged, and also comprising an air supply conduit associated with said opening and nozzle for 35 supplying the air of such mixture, a pump for supplying said nozzle with the fuel oil and a blower for supplying said conduit with air, the nozzle being constructed to form an oil spray of such pattern that the flame produced by the 40 burning of said mixture within the drum will be in out-of-contacting relation with all said walls of said drum, said air supply conduit constituting substantially the sole means of admitting air to said drum.

4. Oil burning apparatus according to claim 3 in which that end wall of the drum which is opposite the end thereof having the opening with which the spray nozzle is associated is also formed with spaced perforations, which perforations also do not exceed approximately 0.018 square inch in transverse cross-section and present approximately from 0.05 to 0.14 square inch of total transverse cross-section per square inch of perforated surface, the total area of perforated surface presented by said perforated end wall and the lateral walls in square inches being arithmetically approximately from 15 to 35 per cent of the arithmetical value of the cubic contents of the drum expressed in cubic inches, the perforations of the lateral walls and of said perforated end wall constituting substantially the sole means of escape of combustion products from the drum.

5. Oil burning apparatus according to claim 3 in which the lateral walls of the drum are substantially cylindrical.

6. Oil burning apparatus according to claim 3 in which the lateral walls of the drum are substantially cylindrical and the end wall of the drum opposite the end wall with which the spray nozzle is associated lies substantially in a plane normal to the longitudinal axis of the drum.

7. Oil burning apparatus according to claim 3 in which the lateral walls of the drum are substantially cylindrical and each end wall lies sub-

stantially in a plane normal to the longitudinal axis of the drum.

8. Oil burning apparatus according to claim 3 in which that end wall of the drum which is opposite the end thereof having the opening with which the spray nozzle is associated is also formed with spaced perforations, which perforations also do not exceed approximately 0.018 square inch in transverse cross-section and present approximately from 0.05 to 0.14 square inch of total transverse cross-section per square inch of perforated surface, the total area of perforated surface presented by said perforated end wall and the lateral walls in square inches being arithmetically approximately from 15 to 35 per cent of the arithmetical value of the cubic contents of the drum expressed in cubic inches, the perforations of the lateral walls and of said perforated end wall constituting substantially the sole means of escape of combustion products from the drum.

9. Oil burning apparatus according to claim 3 in which the lateral walls of the drum are cylindrical and in which that end wall of the drum which is opposite the end thereof having the opening with which the spray nozzle is associated is also formed with spaced perforations, which perforations also do not exceed approximately 0.018 square inch in transverse cross-section and present approximately from 0.05 to 0.14 square inch of total transverse cross-section per square inch of perforated surface, the total area of perforated surface presented by said perforated end wall and the lateral walls in square inches being arithmetically approximately from 15 to 35 per cent of the arithmetical value of the cubic contents of the drum expressed in cubic inches, the perforations of the lateral walls and of said perforated end wall constituting substantially the sole means of escape of combustion products from the drum.

10. Oil burning apparatus according to claim 3 in which the lateral walls of the drum are substantially cylindrical and in which that end wall of the drum which is opposite the end thereof having the opening with which the spray nozzle is associated lies substantially in a plane normal to the longitudinal axis of the drum and is also formed with spaced perforations, which perforations also do not exceed approximately 0.018 square inch in transverse cross-section and present approximately from 0.05 to 0.14 square inch of total transverse cross-section per square inch of perforated surface, the total area of perforated

surface presented by said perforated end wall and the lateral walls in square inches being arithmetically approximately from 15 to 35 per cent of the arithmetical value of the cubic contents of the drum expressed in cubic inches, the perforations of the lateral walls and of said perforated end wall constituting substantially the sole means of escape of combustion products from the drum.

11. Oil burning apparatus according to claim 3 in which the lateral walls of the drum are substantially cylindrical and in which each end wall lies substantially in a plane normal to the longitudinal axis of the drum and is also formed with spaced perforations, which perforations also do not exceed approximately 0.018 square inch in transverse cross-section and present approximately from 0.05 to 0.14 square inch of total transverse cross-section per square inch of perforated surface, the total area of perforated surface presented by said perforated end wall and the lateral walls in square inches being arithmetically approximately from 15 to 35 per cent of the arithmetical value of the cubic contents of the drum expressed in cubic inches, the perforations of the lateral walls and of said perforated end wall constituting substantially the sole means of escape of combustion products from the drum.
